METHOD AND MACHINE FOR KNITTING

Oscar Fregeolle, Central Falls, R. I., assignor to
 Hemphill Company, Central Falls, R. I., a corporation of Massachusetts

Application April 21, 1943, Serial No. 483,869

15. Claims. (Cl. 66—93)

This case concerns an invention in circular, independent needle type knitting machines adapted to knit the so-called Kushion-Foot stockings. In this hosiery pile or terry loops are formed at the inner face of the fabric in such parts of the foot as are desired. Preferably, the said pile or terry loops are formed at the heel and toe and at the sole of such hosiery. If desired, these loops may also appear in the high splice.

In knitting in a rotary fashion, there is no particular difficulty encountered in causing the pile loops to appear at desired wales and courses. The pile yarn is fed over sinker nibs, and sinker loops of that yarn are drawn which are longer and project at the inner side of the fabric. Said loops act to cushion the foot and are especially desired for athletic or military wear. During heel and toe knitting both of which occur while the machine is reciprocating, considerable difficulty is experienced in causing the pile yarn to feed over sinker nibs, especially over all sinker nibs functioning in a course. Once it starts above a sinker nib it will be drawn in that manner for the remainder of the course without any particular trouble, but since the two yarns, that is, the pile yarn and the body yarn, feed fairly close together even with as much separation as is practicable, and converge toward the knitting point when engaged by needles, it is difficult to project a first sinker nib between them. In other words, at the start of a reciprocatory course, the natural tendency of these yarns is to feed into sinker throats despite the fact sinkers are projected inwardly with the intent that their nibs shall separate the yarns.

In the invention herein described a picking action is applied to the leading needle in the short butt group knitting during reciprocatory work, for the purpose of causing that needle to engage only the body yarn to draw it downwardly causing a maximum separation of the two yarns. This accompanied by proper timing of the sinker projection assures that the very first sinker over which the pile yarn might be drawn is actually projected so that its nib separates the yarns after which the pile yarn draws over all sinker nibs and, of course, the body yarn is drawn in sinker throats.

In addition to the picking of needles as above mentioned, the body and pile yarns are fed by specially devised mechanism and in a novel manner to assure the greatest separation of the yarns and also to assure that in the picking of leading

needles as the short butt group moves in either direction, that needle will engage only the lower or body yarn.

The invention is herein described by reference to an illustration of one preferred embodiment of the same.

In the figures of the drawings:

Fig. 1 is a plan view showing part of the carrier ring and yarn lever assembly and showing feeding in a clockwise, reciprocatory stroke.

Fig. 2 is a section through Fig. 1 and illustrating the same mechanism.

Fig. 3 is a plan view similar to Fig. 1, but illustrating only the body yarn feeding means.

Fig. 4 is a section through Fig. 3 showing more of the detail of that body yarn feeding means.

Fig. 5 is a detailed view of the elements shown in Figs. 3 and 4, but as seen from within the circle of needles.

Fig. 6 is a plan view, parts being broken away, showing sinker cams and the pathway of sinker butts in clockwise strokes.

Fig. 7 is a detail view showing certain mechanism as applied to the control of the special pile yarn feeding lever.

Fig. 8 is a detail of that means which is employed to actuate the movable sinker cam.

Fig. 9 is a plan view of the needle pick at the main cam block.

Fig. 10 shows the mechanism of Fig. 9 as seen from the inside of the needle circle.

Fig. 11 is a section taken vertically through the center of the picking mechanism.

Fig. 12 is an elevation of the cam block to which the pick is applied.

Fig. 13 is a detail, greatly enlarged, showing the first needle in the short butt group starting to be picked to engage the lower or body yarn.

Fig. 14 is a similar view slightly more advanced in the cycle, and showing the body yarn engaged by the hook of the leading short butt needle.

Fig. 15 shows what has happened in Fig. 14 as seen from a different view point.

Fig. 16 shows a still further advanced point in the cycle where the nib of the first sinker to engage between the yarns has been projected inwardly.

Fig. 17 is a view showing the knitting detail of Fig. 16, but as seen from a different view point.

Fig. 18 is a detail view showing the pathway followed by a needle which has been picked down and the manner in which the following needle butts ride above the pick itself.

Fig. 19 is an isometric view of a few needles and sinkers and which illustrates the manner in which the yarns are engaged by the needle hooks and in which the pile yarn is separated from the body yarn to be drawn above sinker nibs.

Fig. 20 shows the manner of feeding the pile yarn and the body yarn in counter-clockwise strokes of knitting.

Fig. 21 shows the position of those parts when feeding is in the opposite or clockwise direction.

Fig. 22 is a conventional illustration of a stocking knitted in the manner herein described.

Now referring to the figures of the drawings, in Figs. 1 and 2 there is shown a carrier ring 1, a sinker cam cap 2 and a few of the needles 3 as they are passing the mouthpiece in the carrier ring in a clockwise direction. In the extension 4 to the carrier ring there are pivoted at 5 the usual plurality of yarn levers of which two are important for an understanding of the invention herein involved. A body yarn 6 is fed by the yarn lever generally designated by numeral 7 and a pile yarn 8 is fed by a lever similarly indicated by numeral 9.

In Fig. 2 the needle cylinder 10 has the usual sinker head 11 on which is carried the cap previously indicated by numeral 2. The topmost part of a yarn lever control box 12 is shown and in that control box are a plurality of controlling levers 13 pivoted at 14 each of which is actuated in a well known manner, see U. S. Patent #933,443.

The pile yarn 8 must be fed in such a way that it is delivered out of its eyelet or guide in the lever 9 at a distance from the passing needles, and, in either direction of reciprocation of the needles, will be drawn through the appropriate corner of the mouthpiece. To accomplish this in a simplified and effective manner the lever 9 has been specially constructed so that a spring portion 15 is attached to the part 16 which pivots at 5. A spring 17 urges the lever in a direction so that it remains in feeding position, Fig. 2, except when raised by contact of the end of lever 13 with a lower projection 18 extending beneath the spring part of the lever 15. To the end of the spring portion 15 is soldered or otherwise connected a guide or eyelet 19. The lever is stopped by a screw 16', and by adjustment of that screw, the feeding position of eyelet 19 can be varied.

This lever may be swung from one side to the other since the spring portion 15 is suitably flexible for the purpose. As actually constructed, the portion 15 is bent permanently so that it assumes the position of Fig. 20 unless otherwise affected. In that position the yarn 8 will feed as intended through the corner of the mouthpiece for counter-clockwise strokes or in straight-a-way or rotary work. When clockwise strokes of knitting occur as in knitting a heel or toe, the sinker cam cap will be moved with the cylinder and sinker head 11 and that movement is availed of to bend the spring portion of the lever 15 to the position of Figs. 1 and 21 so that the pile yarn will then feed through the opposite corner of the mouthpiece. A lug 21 is attached at the proper position on the cap 2 and contacts an extending part 22 from the spring part 15 of the lever moving it sideways to an extent desired.

The spring portion of the lever has an upwardly extending projection 23, that extension being for the purpose of maintaining the proper relationship of this lever with its adjacent levers,

The extension 23 projects up further than either of the adjacent levers and when a yarn change is effected, the spring lever 9 cannot interfere with that yarn change nor can that lever become crossed over to assume a wrong position.

The yarn 6, as before stated, feeds through lever 7 and that lever is so designed as to feed its yarn at a low position very close to the center of the mouthpiece. The mouthpiece has a lower plate 24 which is cut away at the center portion so that the end of the lever 7 assumes such a position that the eyelet 19 of the first mentioned or spring lever can swing to and fro above lever 7 without interference.

The lever 7 is really a forwardly extending projection having suitable eyelets through which the yarn is threaded and a part of a vertically disposed rectangular slide 25. This slide 25 moves within a guide generally indicated by numeral 26. A spring 27 maintains it in downward position except when raised by one of the levers 13 which contacts with the engaging part 28 at the lower end of the slide 25.

The lever 7 feeds a body yarn during at least 25 the knitting of those parts of the foot in which pile yarn is incorporated. The yarn lever 9 feeds its pile yarn preferably only during heel and toe knitting. Another lever not necessarily described here, but preferably the lever 29, Figs. 20 and 21, 30 feeds a pile yarn in the high-splice and in the sole of the foot. This lever 29 is what is commonly known as a "jumping finger" and feeds its yarn for a part revolution only.

In Fig. 7 the lug 21 is shown in detail, the same 35 being attached by suitable screws to the cam cap 2. This lug 21 is specially shaped as shown so as to allow space for a movable cam, later to be described, and which is controlled at times to be moved inwardly and at other times, to move out 40 to an inactive position. The surface 30 of the lug 21 is rounded so that whenever the yarn lever 9 is raised to inactive position and is then lowered, the extension 22 on the spring portion of the lever will automatically find its proper position.

In Fig. 6 the cam cap 2 has been cut away to 45 illustrate the sinker cam 31 at the front, the regular sinker cam 32 at the back, and the movable cam 33 cooperating therewith as well as the center sinker cam 34. The center sinker cam is of the usual type and cam 32 has no unusual characteristics. It has a casting off point 35 which corresponds to the casting off point 36 on cam 31, each of these performing its intended function in its respective direction of knitting.

When knitting the pile yarn, since it is drawn over sinker nibs, the sinkers over the nibs of which it is to be drawn must be moved inwardly earlier than usual, and for that purpose, the point 37 on the movable cam 33 functions in counter-clockwise directions of knitting while a correspondingly placed point 38 on the cam 31 performs a like function when the knitting elements are moving in a clockwise direction. Cam 31 need not be movable in a machine for knitting hosiery of this type and, in fact, since all heels and toes are to have the pile loops, all sinkers functioning with that group of needles knitting the pile must be pushed in. Thus the point 38 is always necessary in these clockwise strokes during knitting the heel and toe.

The cam 33 is pivoted at 39 and a spring 40 engageable with the extending end 41 normally moves that cam outwardly. In its outermost position it will have no effect and the only sinker movement during counter-clockwise movement

of the needles will be a casting off action under the influence of the cam point 35. To move the cam 33 inwardly so that its point 37 will function on sinker butts to move their nibs between the yarns, a plate 42 contacts a pin 43. This pin 43 projects downwardly from cam 33 and is contacted by a surface of the plate 42 which is concentric with the needle cylinder and sinker cap. This concentric surface is of sufficient extent so that the pin 43 will be engaged even though the cam cap oscillates to and fro throughout several degrees.

A stem 44 projects outwardly from plate 42 and is guided within a bracket 45 so that it may move radially of the cylinder. A lever 46 is pivoted at 47 and engages a pin 48 by means of its forked end, the said pin projecting upwardly from the stem 44. This lever 46 is moved at appropriate times by means of connections through to the main pattern drum or to some other suitable pattern means. If it is to be controlled so that cam 33 moves out with relatively great frequency, then it would preferably be controlled from the stiper mechanism or by some similar pattern device. A stop 49 prevents outward movement of the cam 33 beyond a predetermined point.

Now referring to Figs. 9, 10, 11 and 12, a cam block 50 is of the usual construction and that cam block would normally be held in a proper position by key 51. The key itself is modified as herein shown by drilling and tapping so that a pin 52 may be inserted in the drilled hole and retained in position by a lock screw 53. This pin serves as a pivot for a yoke generally indicated by numeral 54. The pin 52 has a collar 55 and is threaded for a retaining screw 56 which with a washer 57 completes the bearing for the yoke. This yoke may swing to and fro and is so constructed as to have the inclined sides 58 and 59 down the inner surfaces of which a pick 60 may be guided. The yoke swings to and fro throughout a small angle and also carries at its upper end a cam 61 which serves to guide needle butts which have passed up over the end of the stitch cams 62 or 63 so that the leading one of those needle butts will be engaged by the pick.

The pick itself is universally pivoted. It is connected to swing laterally in a bearing within the spindle 64. That spindle is in turn movable in the bracket 65 so that the pick may be swung vertically. A spring 66 is so attached to the bracket and to a projecting element 67 from the pick that it serves by its tension to retain the pick upwardly in the position of Figs. 10 and 11, except as it is otherwise moved.

As just stated the pick will be engaged by the first needle butt to move up cam 62 or cam 63 depending upon the direction of knitting. Such a butt will, when it strikes cam 61, swing the cam to the left or right as the case may be and then pass down the cam and engage the notch in the end of the pick. Then the movement of the needle butt will force the pick to swing and move down the incline 59 or 58. This downward movement continues until the receding motion of the butt and pick causes them to disengage.

Figs. 13-20 illustrate the feeding and knitting of the body and pile yarns, respectively, in the first full course of the heel knitted in counter-clockwise direction, needle 68 being the last short butt needle to knit in the previous clockwise course and, consequently, having been picked up at the beginning of the first counter-clockwise course. Of course, all the needles of the long butt group

have been raised previously to the so-called instep height.

Thus the short butt needle herein designated by numeral 69 has been raised as its butt passed up cam 62, then lowered down cam 61 on the yoke 54 and the butt 70 of the needle 69 is shown in Fig. 13 just as it has engaged pick 60. Of course, the yoke has been swung to the left.

The spring yarn lever has been released by the lug 21 and has moved over to the left, Fig. 13, so that eyelet 19 feeds the pile yarn very close to that corner of the mouthpiece. Of course, yarn 6 feeds in the middle of the mouthpiece and the timing is such that pick 60 will move needle 69 down to engage yarn 6 at such a time that it could not possibly engage yarn 8. The needle 69 after it has engaged yarn 6 is shown in Figs. 14 and 15.

In Fig. 16 the cycle has progressed to a point where needle 69 has been picked down by pick 60 so that it has drawn the yarn 6 to the level of sinker throats. This picking movement assures that the body yarn is at that level when sinkers move in. It also pulls the fabric down, the same having a tendency to creep upward after sinkers 20 have been withdrawn by the center sinker cam 34, see Fig. 13. It also, in combination with the spaced feeding illustrated in Figs. 13 and 14, assures that yarns 6 and 8 are maintained sufficiently far apart so that the sinker nibs when projected 25 inwardly, will engage between them. Of course, the cam point 37 is in the position of Fig. 6 and sinkers 71 have their nibs 72 pushed inwardly at that particular point. In Figs. 16 and 17 it can be seen that the needle 68 with the instep 30 group has both yarns about its shank, the needle 69 having been picked down drawing yarn 6 down, but not engaging yarn 8. Yarn 8 is not engaged or drawn down until the next following needle 35 73 is lowered by its stitch cam. Nibs of the next two sinkers following the sinker numbered 71 are projected in so that yarn 6 is held in their throats while the yarn 8 passes above their nibs. Thus the very first sinker which could move between these yarns to draw a pile loop is thus effectively caused to engage the pile yarn over its 40 nib. 45

In Fig. 20 the cycle has progressed to that point where needle 69 has drawn its stitch from yarn 6 and has cast off the previously held loop. Yarn 8 50 has been measured over the top of two sinker nibs and is being drawn by the next needle 73 and will be so drawn by all following needles in the group. All needles after needle 69 draw both yarns 6 and 8, drawing yarn 6 in the throats and

55 yarn 8 over the nibs. In this view the relative feeding positions of the yarns in the mouthpiece is well illustrated. In each of these figures the dot and dash lines at 74 serve to show the throat level of sinkers while the line 75 shows the level 60 of the tops of nibs.

In Fig. 21 the relative positions of yarn feeding levers 7 and 9 is shown for clockwise strokes of knitting. It is to be understood that the picking movement and, in fact, conditions of feeding and 65 drawing the yarns is the same in this direction as that just described in respect to counter-clockwise strokes of knitting. In that direction the point 38 on cam 31 moves sinkers so that their nibs engage between the yarns. Of course, the picking mechanism functions just as it did according to Figs. 13-18, except in the opposite direction.

In Fig. 18 the pathway of needle butts is shown at 76 and those needle butts are illustrated as they 75 ride up front stitch cam 62, then down under cam

61 and draw stitches beneath the rear stitch cam 63. The leading needle 69 does not engage the stitch cam 63 until after it has been released by the pick 60. When released it moves along in an independent pathway 77 until engaged by cam 63. Here the pick 60 has been moved back by spring 66, but cannot return to its topmost position until all the short butt needles have passed. Those short butt needles ride above the end of the pick after the same has been released from the butt of needle 69. A similar mode of operation prevails for the opposite direction of knitting.

As the narrowing of the heel progresses the last short butt needle to knit in any course will be picked up at the beginning of the succeeding course by the usual narrowing picks thus placing it in the long butt group and the succeeding needle then becomes the first short butt needle and this will be acted upon by pick 60 after passing over stitch cam 62 or 63 and under cam 61. During widening the first needle butt which engages either one of the stitch cams will be picked down by pick 60. In every case the needle picked down by pick 60 will carry body yarn 6 with it and provide effective separation between the body yarn and the pile yarn to insure that the first sinker nib projected inwardly will pass between them.

In Fig. 19 the hook of needle 69 is shown engaging and having drawn yarn 6 in the throats of the first two sinkers 71. Nibs 72 have yarn 8 drawn over them as needle 73 is moved downwardly and the same action will continue as following needles draw yarn 8 over nibs and yarn 6 in sinker throats.

In Fig. 22 there is shown a stocking which has a top 78, leg 79 and a foot which includes the toe 80, sole 81, heel 82, high-splice 83 and instep 84. Here the heel, sole and toe have pile loops throughout their entire extent. By the mechanism described each loop in each course will have a pile loop at its sinker wale, the first such loop in each reciprocating course really extending over two sinker wales and the intervening needle wale. Heretofore, it has been possible at best to have a pile loop in about the third or fourth loop from the leading needle loop in reciprocating work.

It is not necessary to withdraw pick 60 during rotary work since the pick will merely ride underneath needle butts once that work has started. However, if desired, mechanism may be provided to hold the pick 60 downwardly or to withdraw it to an inactive position.

Operation

At the start of knitting a stocking any top desired may be formed such as a mock rib top having elastic yarn or not, as the case may be, or a true rib top may be transferred to the needles. Then the leg is knitted in the usual manner with or without a reinforced high-splice 83 as desired. At the start of knitting in the heel there is a yarn change effected to feed yarns 6 and 8. At such a yarn change, the plate 42 is moved outwardly so that cam 33 will be moved out by spring 40. Then nibs of sinkers will not interfere with the change of yarns.

The lever 7 is moved to the feeding position and lever 9 is also moved to its feeding position and, of course, prior to the first clockwise stroke in the heel, the so-called instep cams will have moved all long butt needles to the instep position.

From that point on pick 60 will move the leading needle in the short butt group downwardly

as illustrated and described herein. That will separate the yarns and allow the nibs of the sinkers on either side of the needle referred to to move between yarns 6 and 8. The yarn feeding lever 9 automatically takes the position of Fig. 20 in counter-clockwise strokes and in clockwise strokes is moved over to the position of Figs. 1 and 21 by the lug 21 on the sinker cam cap 2. Narrowing and widening progress throughout the heel knitting and that causes certain of the short butt needles to operate temporarily with the long butt group. However, picking continues as above described so that the operation as here illustrated is not altered except for the number of needles actually engaging and drawing yarns 6 and 8 at different points in the knitting of the heel.

After finishing the heel the foot is knitted with the pile yarn appearing in the sole portion only. That pile yarn may be yarn 8, or more preferably it will be a separate yarn knitted by the lever 29. In that event yarn lever 9 will be raised to inactive position and lever 29 will move down to feeding position. It is only necessary to withdraw cam 33 in the event a yarn change is made with respect to yarn 6 or any other yarn feeding in the throat.

Lever 29 has mechanism affecting it by means of which it feeds for half a revolution, and is withdrawn during the other half revolution. Thus the pile yarn will be drawn over sinker nibs at the sole side of the stocking only and will be floated across to the opposite side, said floats being cut later in any desired manner.

After knitting the sole of the foot, a change is made and the toe is formed in a similar manner to that described with respect to the heel.

The invention has been described by reference to a specific embodiment of the same in a typical hosiery machine. This description is illustrative only and is not to be taken in a limiting sense since many variations may be resorted to which would fall within the scope of the invention as originally conceived. The invention is defined in the appended claims.

I claim:

1. A method of increasing the effective separation between two feeding yarns which are to be knitted at a common knitting point which includes the steps of feeding one of said yarns below the other engaging the lower of said yarns only in a needle hook and drawing said needle downwardly before the next following needle engages both of said yarns.

2. A method of increasing the effective separation between two feeding yarns so as to project sinker nibs between said yarns which includes the steps of feeding a topmost yarn above and angularly spaced from the other yarn, engaging the said other or lower yarn in the hook of a needle and drawing said needle downwardly to pull that yarn down and away from the topmost yarn and projecting sinker nibs inwardly before they are engaged by the topmost yarn and after the lower yarn has been drawn down to the level of sinker throats.

3. A method of knitting reciprocating work in a circular, independent needle knitting machine which includes the steps of feeding two yarns, one above the other and laterally spaced therefrom in the direction of knitting, engaging the lowermost of said yarns in a needle hook and picking that needle downwardly to draw that yarn to the level of sinker throats and projecting sinker nibs inwardly so that the said lowermost yarn is en-

gaged in the throats thereof prior to engagement of the topmost yarn over the nibs of said sinkers.

4. Feeding means for a circular, independent needle knitting machine which includes in combination a mouthpiece, a yarn lever substantially at the center of said mouthpiece and so constructed as to feed its yarn at a low level in that mouthpiece and a second feeding lever constructed so as to be flexed laterally and being operable at such a height as to be moved across the top of the first mentioned lever without interference therewith.

5. Feeding means for a knitting machine including in combination a mouthpiece, a plurality of yarn feeding levers vertically movable in said mouthpiece and one lever among said plurality constructed so as to be flexed laterally toward either corner of the mouthpiece and having a flexible, upwardly projecting extension so constructed that when said flexible lever is moved upwardly the extension will guide it to its proper position between the next adjacent levers.

6. A yarn feeding lever for a knitting machine having in combination a pivoting support, a flexible portion extending from said support and having at its end a yarn guiding eyelet and an extension projecting from the said flexible portion of the lever for maintaining it in position between adjacent levers.

7. A yarn feeding lever for a knitting machine having in combination a supporting part adapted to be swung about a pivot, an extending flexible part connected to said first mentioned portion and having a yarn guiding eyelet at its end, an extension for maintaining said lever in proper relationship between its adjacent levers and a second projecting portion by means of which the flexible part of the lever may be bent in one direction.

8. In a knitting machine the combination of yarn feeding means including a mouthpiece, means for feeding two yarns in said mouthpiece, one said yarn through a corner of the mouthpiece and the other yarn adjacent the center of the mouthpiece and lower than that at the corner, a group of needles and sinkers, said sinkers having nibs adapted to be projected between the feeding yarns, and picking means for drawing a needle downwardly to engage the yarn fed centrally of the mouthpiece prior to the point at which sinker nibs are projected between the yarns.

9. In a knitting machine of the circular, independent needle type the combination of yarn feeding means which includes a mouthpiece, means for feeding two yarns in said mouthpiece, one said yarn through a corner of the mouthpiece and the other at a point adjacent the center of the mouthpiece and lower than the corner through which the first yarn is fed, a group of needles and sinkers, said sinkers having nibs, and both the needles and sinkers being adapted to be reciprocated to and fro past the mouthpiece and picking means at the mouthpiece for picking down a needle in said group so that it will engage the lower feeding yarn only in its hook thereby to draw that yarn downwardly and away from the yarn feeding through the corner of the mouthpiece.

10. In a circular, independent needle knitting

machine, the combination of needles and sinkers, a cam block having stitch cams and a mouthpiece in which are operatively positioned a plurality of yarn feeding levers, a pick for needles positioned adjacent the center of said cam block and operable between the stitch cams for picking down a needle in a group of needles as they pass the said mouthpiece in either direction.

11. In a circular, independent needle knitting machine the combination of needles and sinkers adapted to be reciprocated to and fro, a mouthpiece having yarn feeding levers therein, a cam block at the mouthpiece having stitch cams and a picking mechanism which includes a yoke, a center cam and a pick, the said center cam being so constructed as to move needles downwardly to engage the pick after said needles have been raised over the top of either one of the stitch cams.

12. In a circular, independent needle knitting machine, a cam block, a front and a rear stitch cam, a yoke constructed to swing to and fro throughout a slight angle, a pick within said yoke said yoke having a cam positioned between the stitch cams and so constructed that it will move needles raised above the stitch cams to a position to be engaged by the pick.

13. In a knitting machine the combination of a carrier ring, a sinker cam cap reciprocable throughout a predetermined angular extent, yarn feeding means on said carrier ring including a yarn feeding lever constructed at least in part from relatively flexible material so as to be readily bent in a lateral direction, a lug on said sinker cam cap engageable with a part of said lever and operable in at least one direction to flex the lever from one feeding position to an opposite feeding position.

14. In a circular, independent needle knitting machine the combination of a carrier ring, a sinker cam cap reciprocable to and fro throughout a predetermined angular extent, a yarn feeding means including a plurality of feeding levers, a mouthpiece and one of said levers being supported at the center of the mouthpiece while a second said lever is positioned adjacent one side of the mouthpiece and is so constructed as to be readily flexed laterally, the said lever normally being bent in a direction so that it will feed its yarn through one corner of the mouthpiece, a lug on the sinker cam cap engageable with a part of said flexible lever and operable to bend the lever over the first mentioned lever so that it will feed its yarn at the opposite side of said centrally located lever and in the opposite corner of the mouthpiece.

15. A method of reciprocatory knitting on a circular, independent needle, knitting machine which includes the steps of feeding two yarns one below the other to the needles of a group of needles said group including less than the entire number of needles, picking down the first needle of that group which will knit in a given course so as to engage and draw down the lower yarn only to thereby increase the effective separation between the two yarns, and projecting sinkers inwardly so that their nibs will pass between the said two yarns.

OSCAR FREGEOLLE.
